MECHANISM FOR SEQUENTIAL CONTACT SWITCHES

Edwin August Miller, Fairfield, Conn.

Application April 23, 1947, Serial No. 743,265

4 Claims. (Cl. 200—67)

1

This invention relates to mechanism for snap-acting switches and more particularly to such mechanism providing sequential contacts upon a full operation of an actuator.

The objects of the invention are to provide such mechanism that will have high contact pressure for a small size switch; to provide a self-wiping contact action minimizing contact welding; to provide contact action in sequence increasing switch potentialities as a control device; to provide a compact switch having sequential contact action for use where weight and space are given factors; and to provide for a sequential action switch adjusting means for regulating varied sequential contact action.

The applicant is aware that the prior art discloses switch structures embodying sequential contact action with respect to a floating switch blade movable between pairs of fixed stops of which the stops of one pair are variably spaced, one from the other, and differently from that of the other pair, or embodying an actuator carrying spring arms, each of which is connected to a compression arm, said arms being of different lengths.

The applicant is also aware that it is old to provide a compression arm of a cantilever type with a U-shaped loop portion, such arm at one extremity being supported by a rigid base, and also it is old to provide a separate looped spring for a connection between an actuator and a part to be acted upon.

It will be understood, however, as the novel structure of the mechanism is herein disclosed, that the prior art does not anticipate the features of this invention.

Referring to the accompanying drawing, the Figure 1 illustrates the mechanism of the device in unoperated position, a front cover of the insulation casing being removed; Figure 2 is a similar view of the mechanism in partially operated position; Figure 3 is another view of said mechanism maintained in fully operated position; Figure 4 is a plan view of said mechanism, the casing including a cover but a top casing wall is removed; and Figure 5 is a detail illustrating a slight modification with respect to the blade member.

With more particular reference to the accompanying drawing, the numeral 1 designates portions of the insulation casing, and 2 the front cover thereof. The casing cavity 3 is fixedly provided with two pairs of projecting stops 4—5 and 6—7, the stops of each pair being relatively spaced, one from the other, in alignment at op-

2

posite ends of the cavity 3. Positioned within the cavity 3, and bodily movable between stops 5—7 and 4—6, is the switch blade 8 having there-through the elongated opening 9 and carrying at opposite extremities of the blade 8 the contacts 10 and 11 on the upper side thereof and contacts 12—13 upon the lower side, the contacts 10—11 being respectively engageable with the fixed contacts or stops 4—6 and the contacts 12—13 being respectively engageable with the fixed contacts or stops 5—7.

Non-rotatably supported by the base 1 within the passage 14, communicating with the cavity 3, is the push actuator 15 transversely extending as at 23A, through the opening 9 of the blade 8. Opposite lower sides of the actuator 15 are provided with a series of axially spaced notches 16—17.

A pair of relatively opposing compression arms 18—19 is positioned within said opening 9 of the blade 8, each arm having an end carried by an extremity of the blade 8, and an opposite end engaged within a notch 16 or 17 of the actuator 15. One of said compression arms 18—19 is provided with a U-shaped looped portion 20 adjacent its notch engagement.

The actuator 15 is shown in the Figures 1 and 2 with a coil spring 22 to insure return movement of the actuator, but such spring may be omitted if both positions of the actuator 15 are maintained and the lower end of the actuator 23 being adapted for a manual pushing operation.

The normal position of the snap-acting mechanism, illustrated by the Figure 1, may be operated a first step by means of a part-way downward pressure of the push actuator 15. This moves the mechanism to the position illustrated by the Figure 2. Such moved position shows the movable contact 10 in engagement with the stop 4, the movable contact 13 not having broken contact with the stop 7, by reason of the greater force exercised by the compression arm 18, as compared with that of the looped arm 19, the action of the looped arm 19 is retarded until a full operation of the actuator 15. Upon a full operation of the actuator 15 the contact with the stop 7 is broken and the contact 11 is moved into engagement with the stop 6, the switch blade 8 bridging the stops 4—6, as illustrated by the Figure 3. The part-way and full operations of the mechanism enables the employment of stops 4 and 6, each included in separate electric circuits and thus dividing the full operation of the mechanism into two distinct means of device control.

The movements of the contacts 10, 11, 12 and 13 carried by the blade 8 are all snap-acting. While the Figure 1 shows the contact 12 and 13 maintained in engagement with the stops 5-7, respectively, the contacts 10 and 11 may likewise be maintained in engagement with the stops 4 and 6 by omitting the coil spring 22. The actuator 15 may then be operated both ways by manually pushing it in either direction.

As the actuator 15 is partially operated downwardly, both notch-engaged ends of the compression arms 18-19, in their respective notches of the series 16-17, are carried thereby in under-centering relation to the blade 8 whereby the compression arm 18 of greater compressional force operates its end of the blade 8 upwardly engaging the contact 10 with the stop 4. A further operated actuator 15 carries the notch-engaged ends farther downwardly whereby the arm 19 operates the blade 8 to lift its end of the blade 8 to engage the contact 11 with the stop 6.

During the operation above explained, and also the operation of the mechanism in reverse thereof, the snap-acting movement of oppositely carried contacts occur in sequence and all engagements thus made are surface wiping contacts, thereby minimizing the possibility of contact welding.

The wiping engagements by the movable contacts 10, 11, 12 and 13 are provided upon the downwardly movement of the actuator 15 by the greater compressional force exercised by the arm 18, as compared with that of the weaker arm 19, the arm 18 slightly shifting the blade 8 longitudinally one way but, upon the spring 22 or other return of the actuator 15, the release of the arm 19 from a cramped position, occurring with a full operation of the actuator 15 relative to the blade 8, shifts the blade 8 longitudinally the other way.

In the snap-acting switch mechanism above disclosed, there is assured a good contact pressure in all sequential positions of the movable contacts in engagement with stops.

The compression arm 18 being above referred to as the arm having the greater compression force, and the arm 19 as having the weaker force of the two arms, a more definite explanation concerning the reason for the difference in compressional force of these two arms 18 and 19 might be better understood as follows:

Before assembling the parts of the mechanism, the compression arm 18 has the tendency to lie substantially in the plane of the blade 8, as illustrated by the Figure 5. Upon assembling, the compression arm 18 is bent slightly upwardly with its free end held in a notch-engagement with the actuator 15 above the blade 8, as illustrated by the Figure 1, and thus maintained in readiness to be snap-actingly moved downwardly as the actuator 15 is operated to carry the notch-engaged end of the arm 18 to below the blade 8. This action so distorts the blade 8 as to move the contact 10 with a snap-action into engagement with the stop 4, as illustrated by the Figure 2. In other words, the compression arm 18 having the natural tendency to lie substantially in the plane of the blade 8, as illustrated by the Figure 5, responds alike to be positioned above or below the blade 8 according to which ever way its notch-engaged end is carried upon operation of the actuator 15, the full compressional force of the arm 18 being directed substantially along the plane of the blade 8.

Because of the biased or looped portion 20

of the compression arm 19, that portion 20, before and following the assembly of the mechanism, lies below the blade 8 although its notch-engaged end is held above the blade 8, as illustrated by the Figure 1. Therefore, upon the operation of the downwardly pressed actuator 15, it is the compression arm 18 that responds more readily for a snap-acting movement from an over-centered to an under-centered position relative to the blade 8, the snap-action of the arm 19 being delayed until a full operation of the actuator 15 when the biased or looped portion 20 of the compression arm 19 becomes cramped and causing the remaining portion of the arm 19 to be under-centered with relation to the blade 8 and to so distort the blade 8 as to move with a snap-action the contact 11 into engagement with the stop 6.

However, with a reversed movement of the switch mechanism, by means of the spring 22, or manual pressure against the lower end 23 of the actuator 15, the contact 11 in engagement with the stop 6 is the first to break engagement because of the forceful release of the cramped condition of the biased or looped portion 20 of the compression arm 19 giving the arm 19 increased compressional force substantially along the plane of the blade 8, said increased force being greater than that of the compression arm 18. By reason of such increased force, the arm 19 is moved to over-centered position with respect to the blade thereby being distorted and moving with a snap-action the contact 13 into engagement with the stop 7. As the spring or manual pressure continues to move the actuator 15 upwardly, the compression arm 18, now in sequence, is over-centered with respect to the blade 8 whereby the blade 8 being distorted moves and engages with a snap-action the contact 12 with the stop 5, said blade 8 bridging the stops 5 and 7.

While the structure of the mechanism, as herein shown and specified, provides for a definite manner of sequential action of movable contacts 10, 11, 12 and 13, it is to be understood that, by readjusting the notch-engaged ends of either or both compression arms 18 or 19 in engagement with any of the series of notches 16-17, a variance of such sequential contact action may be accomplished and is herein intended to be included as within the scope of this invention.

The modified structure of a detail of the mechanism, illustrated by the Figure 5, shows a compression arm 19A having a U-shaped biased or looped portion 20A secured with, and upon, the top surface of an extremity of the switch blade 8A by means of a rivet 21 the head of which serves as a contact 11A and the opposite end of said rivet 21 as a contact 13A carried by the blade 8A. If desired, both compression arms 18 and 19A likewise may be provided with such attached compression arms.

I claim:

1. A snap-acting switch mechanism comprising a base; pairs of upper and lower fixed stops provided by said base; a contact-carrying switch blade bodily movable between said upper and lower stops and having an opening therethrough; a non-rotatable push actuator slidably supported by said base and extending transversely to, and movable within, said opening; notches with which the actuator is provided upon opposite sides and lower end thereof; a pair of relatively opposing compression arms within said opening, each arm having an end carried by an

extremity of said blade, and an opposite end engaged within one of said notches; and a looped end portion of one of said compression arms adjacent its notch engagement, said looped portion depending from said arm below said blade; a lowered position of said looped portion resulting from a partial actuator operation moving with a snap-action the other compression arm from an over-center to an under-center relation to said blade, and also in a contact engagement of said blade with one of said upper stops; a cramped position of said looped portion resulting, upon a full operation of said actuator, in a snap-acting under-centering movement of the looped compression arm with respect to said blade; and a sequential contact engagement of said blade with the other of said upper stops, said engagement being in sequence with respect to the contact engagement of said blade with an upper stop.

2. A snap-acting switch mechanism, as set forth in claim 1, said mechanism including a reversed movement thereof upon the operation of said actuator manually or by a return spring; a released position of said cramped looped portion upon the partial return of said actuator resulting in a snap-acting over-centering movement of the looped compression arm with respect to said blade, and also in breaking and making contact movement from an upper to a lower of said stops; and a fully returned position of said actuator resulting in a snap-acting over-centering movement of the other of said compression arms with respect to said blade, and also in a breaking and making contact engagement from an upper to a lower one of said stops, said last contact engagement being in sequence with respect to the other engagement of said blade with a lower one of said stops.

3. A snap-acting switch mechanism, as set forth in claims 1 and 2, said mechanism including surface-wiping contact engagements with said stops upon a longitudinally shift-movement of said blade resulting from the greater force alternately exercised by said compression arms

upon the operation of said actuator by manual or spring return means.

4. A snap-acting switch mechanism comprising a base; pairs of upper and lower fixed stops provided by said base; a contact-carrying switch blade bodily movable between said upper and lower stops and having an opening therethrough; a non-rotatable push actuator slidably supported by said base and extending transversely to, and movable within, said opening; notches with which the actuator is provided upon opposite sides and lower end thereof; a pair of relatively opposing compression arms within said opening, each arm having an end carried by an extremity of said blade, and an opposite end engaged within one of said notches; and a looped portion on one of said compression arms, said looped portion depending from said arm; a lowered position of said looped portion resulting from a partial actuator operation moving with a snap-action the other compression arm from an over-center to an under-center relation to said blade, and also in a contact engagement of said blade with one of said upper stops; an increased compressed position of said looped portion resulting, upon a full operation of said actuator, in a snap-acting under-centering movement of the looped compression arm with respect to said blade; and a sequential contact engagement of said blade with the other of said upper stops, said engagement being in sequence with respect to the contact engagement of said blade with an upper stop.
